UNITED STATES PATENT OFFICE.

SAMUEL C. TAYLOR, OF CHICAGO, ILLINOIS.

WINDOW.

SPECIFICATION forming part of Letters Patent No. 445,384, dated January 27, 1891.

Application filed March 31, 1890. Serial No. 345,952. (No model.)

To all whom it may concern:

Be it known that I, SAMUEL C. TAYLOR, of Chicago, Illinois, have invented certain new and useful Improvements in Windows, of 5 which the following is a specification.

The object of my invention is to provide for the ready insertion and removal of window-sash and to adapt sashes provided with cords and weights to be tipped forward for 10 cleaning their outer sides.

My invention is applicable to single or double sash windows, and when applied to a double-sash window both sashes can be readily inserted into and removed from the frame 15 or tipped, as and for the purpose described.

In carrying out my invention I modify the usual construction of window-frames by setting the jamb of the frame so as to form an obtuse angle to the sill, and thereby I am enabled, when two sashes are used, to raise or lower either of the sashes without interference between their weights or cords. This arrangement also permits the connection of the ends of the sash-cords to the rear faces 25 instead of the edges of the sash, and thereby the cord is prevented from interfering with the movement of the sash in tipping the latter forward for cleaning. The upper sash, where two are used, may run in ways formed 30 by strips or stops in the usual way; but the stops for the lower sash are entirely omitted in my improved construction, and instead thereof pins or pintles are affixed in the edges of the sash toward the top and bottom there- 35 of, and the frame has grooves forming ways, within which these pintles move when the sash is being manipulated. These grooves are interrupted at a point above the mid-height of the frame to permit the upper pintles to pass out of the grooves when it is desired to tip the window.

To adapt my invention to sash of the ordinary construction, I prefer to make strips of the usual height and thickness and adapted 45 to be secured to the edges of the lower sash. To the rear faces of these strips I secure the ends of the sash-cords in any convenient manner, and from their outer edges the pintles before mentioned project.

50 In the drawings, Figure 1 is a front elevation of a window-frame with two sashes and embodying my improvements. Fig. 2 is a ver-

tical section on line 2 2 of Fig. 1, and Fig. 3 is a transverse section on the line 3 3. Fig. 4 is a front elevation of a single sash with 55 transom. Fig. 5 is a sectional elevation on the line 5 5 of Fig. 4, and Fig. 6 is a transverse section on the line 6 6 of Fig. 4.

In the drawings, 7 represents the sill, and 8 the jambs, of the window-frame. The frame 60 may be of the usual construction, except that the jambs are set at an obtuse angle to the sill, their inner edges the farthest apart, as clearly shown in Figs. 3 and 6.

9 and 10 are stops for the upper sash, the 65 former being cut away at about the normal position of the meeting-rails. Within the triangular spaces bounded by the face of the jambs, these stops 9 and 10, and the sash-frames 11 and 12 the cords 13 operate, said 70 cords being carried over the sheaves 14, set in the jambs 8. In the space behind the jambs the weights are arranged to move, and instead of being confined to move within a space of four to six inches, the usual width of jamb, 75 the available space is much greater, owing to the manner of setting the jamb and sheaves, which permit the weights to travel on opposite sides of a vertical plane passing through the sash at right angles. Strips 14^a are se- 80 cured to the edges of the lower sash by screws or in any other convenient way, and the sash-cords are secured to the rear faces of these strips. From the outer edges of these strips project the pintles 15 16, which are adapted 85

to run in a groove 17, formed by rabbeting the edge of the casing 18. The casing is cut away on its edge, as at 19, just above the plane of the meeting-rails, to permit the pintles 15 to leave the groove 17 when it is desired to 90 tip the sash forward, as shown in Fig. 3, in which position the pintles 16 form pivots on which the sash is rocked, the weight supporting its upper end. In this movement it is evident that the sash-cord does not impede 95 the free manipulation of the window, as it would if secured to the edge of the sash. The auxiliary strips serve to build out the lower sash to compensate the peculiar setting of the jamb, and as they are inexpensive and quickly 100 applied their use is preferred to the alternative of constructing the sash of unusual width.

In fitting the sash, the pulleys having been

properly set and the stops affixed, the cords or chains are attached to the rear faces of the side sills of the sash frame. The upper sash is then put in place by inserting it from beneath the front stops and shoving it up to place. The lower sash is then put in place, the strips 14^a having been secured thereon, by first passing the pintles 16 through the apertures 19, and then the sash is pushed down until the upper pintles are opposite the openings 19, when they are passed through, and the window can then be run up and down freely without liability of passing out of place, the weights tending to keep it in proper position.

15 By reversing the movements just described both upper and lower sashes can be readily removed without taking out the stops; but it is not necessary to entirely remove them for cleaning the outside. Hence when desired to 20 clean them the upper pintles of the lower sash are passed through the openings 19, and the sash can then be tipped forward for cleaning.

In the construction shown in Figs. 4, 5, and 25 6 my invention is shown as applied to a single-sash window with a transom. In this example the ways 17 are formed by a groove in a vertical strip 17^a; but they may be formed in the face of the jamb. In this instance also a sheave 13^a is employed to give proper direction to the sash-cord.

I claim—

1. A window-frame having the jambs thereof set at an obtuse angle on the sill and facing outwardly, in combination with sash-frames, the lower one of which is wider than the upper to correspond to the setting of the jambs, cords having counterbalance-weights and connected to the sash-frame near their upper ends, and pintles projecting from the edges 35 40 of the frames into ways provided in the frame, and said ways having transverse apertures

therin through which the pintles may be inserted and removed, substantially as described.

2. A window comprising, in combination, 45 jambs set at an obtuse angle on the sill, a counterbalanced sash-frame arranged to move in ways, said ways having apertures therein, and pintles projected from the edges of the sash-frame and into said ways and adapted 50 to pass through said apertures, whereby the sash may be tipped to permit access to its outer side, substantially as described.

3. In a window, the combination, with jambs set at an obtuse angle on the sill, of outer and inner stops for the sash-frames, set at right angles to said frames, to provide passages for suspending cords, said cords secured to the rear sides of the sash-frames, the lower sash having its side margins extended to correspond with the setting of the jambs by strips secured to the margins, pintles projecting from said strips toward the ends thereof, ways wherein the pintles travel, and apertures in said ways to permit the passing 65 through of the upper pintles, whereby the lower sash-frame may be tipped to permit access to its outer side, substantially as described.

4. In a window, the combination, with jambs 70 set at an obtuse angle upon the sills, whereby to provide elongated weight-pockets, of sash-frames having counterbalancing weights moving within said pockets, and the lower sash being wider than the upper to correspond to 75 the setting of the jambs, substantially as described.

SAMUEL C. TAYLOR.
